UNITED STATES PATENT OFFICE.

ROBERT H. STOLTZ, OF RICHMOND, VIRGINIA.

DESIGN FOR A DISH.

47,368.

Specification for Design. Patented May 18, 1915.

Application filed February 19, 1915. Serial No. 9,461. Term of patent 14 years.

To all whom it may concern:

Be it known that I, ROBERT H. STOLTZ, a citizen of the United States, residing at Richmond, in the county of Henrico and State of Virginia, have invented a new, original, and ornamental Design for Dishes, of which the following is a specification, reference being had to the accompanying drawing, forming part thereof.

The figure is a perspective view of a dish, showing my new design.

I claim:

The ornamental design for a dish, as shown.

ROBERT H. STOLTZ.

Witnesses:

IVY E. SIMPSON,
PHILOMENA A. ROCKELLI.
